UNITED STATES PATENT OFFICE.

WILLIAM J. REGAN AND ENOCH GEORGE, JR., OF PITTSBURGH, PENNSYLVANIA, AS
SIGNORS TO THE McCONWAY & TORLEY COMPANY, OF PITTSBURGH, PENNSYLVANIA, A CORPORATION OF PENNSYLVANIA.

DRAFT APPLIANCE FOR RAILWAY CARS.

Application filed June 1, 1926. Serial No. 112,862.

This invention relates to draft appliances for railway cars and has for its object to provide a simple construction in which a draft yoke device is reliably and efficiently connected to a car coupler designed to swing laterally through a comparatively wide angle when the car to which it is attached passes around curves. A further object of the invention is to produce compact and efficient 5 means for pivotally connecting the head of a car coupler to a shank member adapted to be operatively attached to a yoke device through the instrumentality of a draft key.

A primary feature of the invention consists 10 in operatively connecting a car coupler to a yoke device by means adapted to transmit draft forces to the latter, and in providing the coupler with a head portion and a shank portion which are pivotally connected in advance 15 of the means for attaching the coupler to the yoke, the means for pivotally connecting the head and shank being disposed wholly above the under face of the said shank.

A further and more specific feature of 20 the invention consists in providing a coupler head member at its rear end and a coupler shank member at its forward end with overlapping pivot lugs, one of said lugs in each of the members being formed with a slot to 25 receive a key, and in providing a connecting pivot pin fashioned with a key portion intermediate its ends, the said key portion being adapted to be received by the slots and the latter being out of vertical alinement in 30 all normal relative positions of the coupler head and shank.

In the drawings illustrating the invention, the scope whereof is pointed out in the 35 claims:—

40 Figure 1 is a plan view of a railway draft appliance embodying the invention, portions of the arms or straps of the yoke device being omitted.

45 Figure 2 is a detail view, partly in elevation and partly in vertical section, of the preferred means for pivotally connecting the coupler head and shank members.

Figure 3 is a section on the line 3—3, Fig. 1.

50 Figure 4 is a plan view of a portion of the mechanism showing a modified form of pivotal connection between the coupler head and shank members.

Figure 5 is a view, partly in elevation and

partly in vertical section, of the form of pivot connection illustrated in Fig. 4.

55 In the drawings, 1 is the head portion and 2 the shank portion of a car coupler, the latter preferably being operatively connected to a draft yoke 3 by means of a standard draft key 4 passing through the shank or member 60 and through the customary key slots 5 in said yoke.

The coupler head 1 is pivotally connected to the shank member 2 in advance of the key 4 by which draft forces are transmitted to the 65 yoke device, such pivotal connection preferably being effected by means of a vertically extending pivot pin 6 which passes through correspondingly perforated overlapping pivot lugs with which the adjacent ends of the 70 head and shank are respectively provided. The pivot lugs of the coupler head member preferably comprise an upper lug 7, a lower lug 8 and an intermediate lug 9, while the shank member 2 may advantageously be fashioned at its forward end with a pair of spaced lugs 10 between which the intermediate member 9 of the coupler intervenes. The head member 1 is formed with curved bearing surfaces 11 for cooperating with the correspondingly curved end faces or bearing surfaces 12 of the pivot lugs 10 with which the shank 2 is provided. Similarly the shank 2 is provided toward its forward end with concavely curved bearing surfaces 13 for cooperating with the correspondingly curved end faces 14 of the pivot lugs 7, 8 and 9. By this means ample bearing area is provided in all positions of the coupler head for transmitting buffing shocks to the shank member 2.

90 Between its ends the pivot pin 6 is provided with a rearwardly extending key 15, while the upper pivot lug 7 of the coupler head member and the adjacent pivot lug member 10 of the shank are provided with 95 corresponding key ways or slots 16 and 17, respectively. The slots 16 and 17 are so positioned that they are out of alinement with each other in all relative positions which the 100 coupler head 1 and shank 2 can assume in service. Before the coupler is mounted upon the car the pivot lugs or straps of the head member 1 are inserted between the pivot lugs at the forward end of the shank member 2 105 and the head is swung toward the knuckle.

side of the coupler until the key way or slot 16 is directly over the key slot 17 of the shank member. The pivot pin 6 may then be inserted in the openings of the several pivot lugs, the key extension or lug 15 on the pin passing through the slot 16 in the upper pivot lug of the head and entering the slot or recess 17 in the adjacent pivot lug 10 beneath. The coupler head may then be moved into longitudinal alinement with the shank member 2, thereby locking the connecting pin 6 in place. As the side clearance afforded in the coupler carrier (not shown) will not permit the head 1 to swing around far enough to bring the key slots 16 and 17 into vertical alinement when the coupler is in place, it will be perceived that the pivot pin is thus securely maintained in proper assembled position when the device is in service. A pivotal connection of this character permits the pivot pin to be positioned wholly within the lines of the coupler, thus leaving no portion of it projecting below the under face of the stem or shank member 2. This is advantageous in that it enables the pin to be located in any desired position forward of the yoke without fear of interference with other parts of the car equipment.

Figs. 4 and 5 show a modified form of construction for pivotally connecting the coupler head to the shank member, the pivotal connection being constituted by trunnions 18 cast as an integral part of the coupler head 19. In this type of flexible connection the shank member 20 of the coupler is provided at its forward end with spaced pivot lugs 21 having cylindrical openings 22. After the shank has been cast and dressed it is set in a prepared mold and the coupler head is cast in assembled relation thereto. The trunnions 18 project vertically in opposite directions from a centrally disposed lug 23 which intervenes between the pivot lugs 21 of the shank member. The portion of the lug 23 which extends rearwardly of the trunnions is formed with a curved bearing face 24 which cooperates with a correspondingly curved bearing face 25 disposed between the pivot lugs of the shank; and the forward ends of the pivot lugs of the shank are fashioned with curved bearing faces 26 which cooperate with correspondingly curved surfaces 27 on

the coupler head in advance of the trunnions 18. The mode of attachment of the shank member 20 to the yoke device is preferably 55 identical with that heretofore described.

We claim:

1. A railway draft appliance comprising a car coupler, a yoke device, and means for transmitting draft forces from the coupler to the yoke device, said coupler involving a coupler head, a coupler shank, and a pivot pin for pivotally connecting the head and shank forwardly of said means for transmitting draft forces from the coupler to the yoke device, said pivot pin being disposed wholly above the under face of said shank and having interlocking engagement with said coupler preventing its removal in all normal relative positions of the coupler head and shank. 70

2. A railway draft appliance comprising a coupler head provided at its rear end with a plurality of vertically spaced pivot lugs, a shank formed at its forward end with a plurality of pivot lugs, and a pivot pin extending through said lugs for connecting said head and shank, said pin being provided between its ends with a key portion, one of said lugs on the head being provided with a slot to receive said key, and one of the pivot lugs of the shank being provided with a slot to receive said key, said slots being out of vertical alinement in all normal relative positions of the coupler head and shank. 75

3. A railway draft appliance comprising a coupler head provided at its rear end with a plurality of pivot lugs one of which is formed with a key slot, a coupler shank provided at its forward end with a plurality of pivot lugs one of which is formed with a key slot, said slots being out of vertical alinement when said head and shank are in normal positions, and a pin cooperating with said pivot lugs for pivotally connecting the head and shank, said pin being provided with a key adapted to be received by said slots, and said key being adapted to extend between and engage a plurality of said pivot lugs to thereby maintain the pin in assembled relation. 90

In testimony whereof we affix our signatures. 100
